Geo. P. Kimmel

Attorney

UNITED STATES PATENT OFFICE.

JOHN P. SUTTER, OF BUFFALO, NEW YORK.

READING-LIGHT.

1,284,814.

Specification of Letters Patent. Patented Nov. 12, 1918.

Application filed August 2, 1918. Serial No. 248,023.

To all whom it may concern:

Be it known that I, JOHN P. SUTTER, a citizen of the United States, and resident of Buffalo, in the county of Erie and State 5 of New York, have invented certain new and useful Improvements in Reading-Lights, of which the following is a specification.

This invention relates to the class of lighting fixtures, and more particularly to an improved portable reading light or lamp, adapted to be applied to a book, drawing board or the like, for rendering clearly visible the matter thereon, so that one can read comfortably and without eye strain.

10 A further object of the invention is to provide an improved reading light of the class described including a shade or reflector of novel construction and shape, having improved means for detachably engaging the object to which the device is to be applied for reading purposes, the source of illumination being preferably electrical.

With the above and other objects in view, as will appear as the description proceeds, 25 the invention comprises the various novel features of construction and arrangement of parts which will be more fully described herein and set forth with particularity in the claim appended hereto.

30 Reference is had to the accompanying drawings forming a part of this application, in which like reference characters indicate the corresponding parts throughout the several views, in which—

35 Figure 1 is a rear elevation of my improved reading light,
Fig. 2 is a plan view thereof, and

Fig. 3 is a vertical sectional view taken on the line 3—3 of Fig. 1.

40 Referring to the drawings in detail, my improved reading light is shown as comprising a reflector 10 preferably substantially of triangular cross section having a top wall 11 and a rear wall 12, slightly 45 curved and providing concaved or rounded corner portions 13 and 14 designed to facilitate the reflection of the light toward the open front portion 15, which is inclined rearwardly and downwardly owing to the 50 fact that the top part 11 overhangs the bottom portion or wall 16 and projects beyond the same.

From Figs. 1 and 2 of the drawing, it will 55 also be observed that the rear portion is shorter than the front portion, thereby causing the side or end portions 17 to converge

outwardly and forwardly, and inasmuch as the reflector is made of light sheet metal or other suitable material provided with an interior reflecting surface, the light will be 60 thrown outwardly and downwardly upon the object to be supplied with illumination, for reading or other purposes.

The source of illumination may consist of an electric light bulb 18 mounted within 65 the rounded corner portion 13, centrally between the top portion 11 and the back portion 12, the same having connection with a suitable source of electrical energy, consisting of a primary battery, a secondary battery, or the ordinary commercial lighting circuit, in which latter instance a resistance element or rheostat may be interposed in the circuit, owing to the minuteness of the lamp required to provide the proper degree of 75 illumination.

In order to detachably secure the device to a book, drawing board, or the like, a clamp is provided consisting of a plate 19 riveted to the bottom portion 16, as shown 80 at 20, and having a plate 21 hinged thereto, preferably by providing oppositely extending apertured lugs or ears 22 upon the respective plates connected by a pivot pin 23 with an interposed spring 24 designed to 85 normally dispose the clamping jaws 25 of the plates 19 and 21 in clamping relation. The plates are also provided with reduced handle portions 26, so as to permit the clamp 90 to be readily manipulated.

Also, in view of the shape of the reflector, a maximum quantity of light uniformly distributed over the surface to be observed or read can be given, and the device can be easily applied and removed. Also, by reason of the portability of the device, it can be connected with a battery and thereby serve to permit reading outdoors, especially in hot summer evenings, instead of necessitating that one remain indoors. The weight of the 100 device is also negligible, even including a dry cell which may be used for supplying the proper amount of current to the lamp, through the medium of ordinary flexible electrical connection. The device can also 105 be used in dark factories or offices wherein lighting facilities are poor, for reading meters or other purposes.

From the foregoing description taken in connection with the accompanying drawings, it is thought that a clear and comprehensive understanding of the construction,

operation, and advantages of my invention may be had, and while I have shown and described the device as embodying a specific structure, I desire that it be understood that 5 such changes may be made in said structure as do not depart from the spirit and scope of the invention as claimed.

Having thus described my invention, what I claim as new, and desire to secure by Letters Patent, is:

A reading lamp, comprising a reflector of substantially triangular cross section having a top wall and a rear wall sloping slightly forwardly and provided with rounded upper

and lower corners and a bottom portion, 15 said reflector having end walls diverging forwardly and inclined toward said bottom wall at their side edges, and a clamp including spaced plates pivotally connected and spring means between said plates to normally dispose the same in clamping relation, 20 said clamp being riveted to the bottom portion of the reflector and extending forwardly and rearwardly of the said bottom portion, as and for the purposes specified. 25

In testimony whereof I affix my signature hereto.

JOHN P. SUTTER.
